United States Patent Office.

JOHN ROGERS, OF NEW YORK, N. Y.

Design No. 2,983, dated March 31, 1868.

DESIGN FOR A GROUP OF FIGURES.

The Schedule referred to in these Letters Patent and making part of the same.

TO ALL WHOM IT MAY CONCERN:

Be it known that I, JOHN ROGERS, of the city and county of New York, and State of New York, have invented or produced a new and original Design for a Group of Figures; and I do hereby declare that the following is a full and exact description of the same.

The group consists of three figures, and is called "The Council of War." It represents President Lincoln seated and looking at a map, which he holds in his hands. Secretary Stanton stands behind the chair wiping his glasses, while General Grant stands on Mr. Lincoln's right, pointing to the map, all of which is plainly seen in the accompanying drawings:

What I claim as my invention, and wish to secure by Letters Patent, is—
The design for a group of statuary, as herein shown and described.

Witnesses:

J. L. A. WARD,
ROBERT CUSHING.
